UNITED STATES PATENT OFFICE.

JAMES CROKE, OF ARLINGTON, MASSACHUSETTS.

GAS FURNACE FOR PHOTO-ENGRAVERS, ETC.

Application filed September 6, 1922. Serial No. 586,455.

To all whom it may concern:

Be it known that I, JAMES CROKE, a citizen of the United States, residing at Arlington, in the county of Middlesex and State of Massachusetts, have invented new and useful Improvements in Gas Furnaces for Photo-Engravers, Etc., of which the following is a specification.

This invention relates to gas furnaces employed by photo-engravers to burn in certain chemicals applied to metal plates in the process of etching such plates.

A furnace of this character comprises a base having gas-conducting means, a multiple burner receiving gas from said means, and air from the atmosphere, and provided with a multiplicity of burner orifices at which a mixture of gas and air is ignited, and with means for supporting a coated plate above the burner orifices during the burning in operation. The burner orifices are liable to be clogged by melted material dropping from the plates, so that frequent cleaning is necessary.

The chief object of the invention is to provide an improved construction in furnaces of this description, whereby the convenient removal and cleaning of the multiple burner is permitted.

Another object is to permit the employment of a plurality of multiple burner units, each bearing loosely and separably on and independently removable from the base.

Another object is to provide an improved construction of the base and the plate-supporting means associated therewith.

The above-mentioned and other objects are attained by the improvements herein-after described and claimed.

Of the accompanying drawings forming a part of this specification,—

Figure 1 is a plan view of a furnace embodying the invention.

Figure 2 is a fragmentary section on line 2—2 of Figure 1.

Figure 3 is a section on line 3—3 of Figure 1.

Figure 4 is a fragmentary plan view showing a portion of the base.

Figure 5 is a fragmentary plan view, showing a portion of one of the multiple burner units shown by Figure 1.

The same reference characters indicate the same parts in all of the figures.

The base of my improved furnace preferably includes a marginal rectangular frame,

each of the members of which is of angular form, and has a wall or curb portion 12, and an inwardly projecting flange 13. One of the frame members is provided with a gas conduit 14, preferably cast integral with said member and receiving gas through a supply pipe line 15, controlled by a cock 16. Said conduit is provided with a burner nipple 17, having a shoulder 18, said nipple being controlled by a cock 19.

The base also includes upwardly facing burner seats on which a multiple burner may be loosely and removably supported, said seats being preferably embodied in a plurality of cross-bars 20, attached by screws 21 to the flanges 13 of two of the frame members.

I prefer to utilize the rest members or cross-bars 20 to support a plurality of seats, adapted to support a plate or plates 31, at a suitable height above the burner orifices hereinafter described. Said seats are the upper ends of a plurality of studs 22, attached to and projecting upward from the cross-bars 20.

The base may be formed to support any desired number of multiple burner units, each unit being adapted to bear loosely and removably on the cross-bars 20, and provided with a receiving throat adapted to receive gas from a gas outlet on the base, and having air inlets adapted to receive air from the atmosphere.

Each burner is provided also with a plurality of burner orifices, these being spaced below the plate seats when the burner is operatively installed on the base.

The preferred burner construction is as follows: 23 represents a tubular head provided at one side and between its ends with a flaring or conical throat 24, having an end face containing a central orifice 25, adapted to loosely receive the nipple 17, the end face being formed to abut against the shoulder 18, and provided with air inlets 26, through which air enters the throat to mix with the gas delivered by the nipple 17.

With the head 23 are connected a plurality of parallel tubes 28, arranged to bear loosely and removably on the cross-bars 20, and each provided with a plurality of burner orifices 29, in its upper side, the outer ends of said tubes being closed by caps 30.

When the burner and the base are separated, as indicated by Figures 4 and 5, the burner may be operatively installed on the

base by inclining the burner sufficiently to enable the opening 25 to pass onto and receive the nipple 17, and then depositing the tubes 28 on the cross-bars 20, the tubes 6 being thus horizontally supported with their burner orifices facing and spaced below a plate 31, deposited on the plate seats formed by the studs 22.

It will be seen that the burner may be 10 conveniently removed from the base by inclining it to lift the tubes 28, from the cross-bars, and, when it is suitably inclined moving it endwise to withdraw the throat from the nipple 17. When the burner rests 15 on the seats 20, it cannot be moved endwise far enough to withdraw the throat from the nipple, one of the members of the frame 12 constituting a stop limiting the horizontal endwise movement of the burner and preventing the withdrawal of the burner throat 20 from the nipple.

Although I have shown two burner units, it is obvious that the invention hereinafter claimed may be embodied in a furnace having 25 one burner, or more than two burners, and that the form and construction of the base and the burner may be variously modified within the scope of the appended claims.

I claim:

30 1. A gas furnace of the character stated, comprising a fixed base structure including an open frame, spaced apart burner seats within the frame opening, spaced apart plate seats projecting above the frame, and

a gas conduit fixed to one end of the frame 35 and provided with a burner nipple projecting into the frame opening, the opposite end of the frame having a stop spaced from said nipple; and a multiple burner movably supported by the burner seats between said 40 nipple and stop, said burner including a tubular head having a throat loosely receiving the nipple, and parallel tubes resting 45 removably on the burner seats between the plate seats, and provided with burner orifices, the outer ends of said tubes being closed and in close proximity to said stop when the burner is in its operative position, so that the stop prevents endwise displacement of the burner, the arrangement being 50 such that the burner may be inclined to raise the outer ends of its tubes above said stop and permit the withdrawal of the throat from the burner nipple.

2. A gas furnace substantially as specified by claim 1, the said frame comprising a curb portion, a member of which forms said stop, and a flange portion at the lower edge of the curb portion, the said burner seats and plate seats being formed respectively by spaced apart horizontal cross-bars fixed 60 to the flange portion, and spaced apart upright studs fixed to the cross-bars and projecting above the frame.

In testimony whereof I have affixed my 65 signature.

JAMES CROKE.
